UNITED STATES PATENT OFFICE

1,983,010

CARTON

Russell H. Spees, Constantine, Mich., assignor to
Wolverine Carton Company, Wyoming town-
ship, Kent County, Mich., a corporation of
Michigan

Application March 5, 1934, Serial No. 714,023

5 Claims. (Cl. 229—52)

The present invention relates to cartons or containers, particularly for tapering bottles and the like; and its object is to provide such a carton improved in respects hereinafter appearing; and particularly, to provide such a carton comprising a larger lower part and an upwardly tapering smaller part; and further, to provide such a carton having vertical opposite sides or walls provided with openings therethrough whereby they may be readily grasped and carried, said sides being also adapted to be folded intolapping relation wherein said sides are secured together to form the closed top of the carton.

15 These and any other and more specific objects hereinafter appearing are attained by, and the invention finds preferable embodiment in, the illustrative carton particularly described in the body of this specification and illustrated by the accompanying drawings, in which:

Figure 1 is a view in perspective of a carton;

Figure 2 is a view in perspective of the upper portions thereof showing the parts in another position;

25 Figure 3 is a horizontal sectional view of said carton taken on line 3—3 of Figure 4;

Figure 4 is a vertical sectional view of the carton taken on line 4—4 of Figure 3;

30 Figure 5 is a plan view of a blank which may be bent along dotted lines thereof to form the carton; and

Figure 6 is a view in perspective of said blank partially thus bent to form the carton.

In the embodiment of the invention illustrated 35 by these drawings, the carton 1 is made by bending a flat paper sheet or blank 2 of cardboard or the like along the dotted lines shown in Figures 5 and 6 which define the hereinafter described portions of the blank. This blank comprises a rec- 40 tangular middle portion 3 forming the bottom 4 of the carton, a pair of rectangular portions 5 at the opposite sides of said middle portion and forming the sides 6 of the lower and larger part 7 of the carton these portions 5 each having a pair 45 of end flaps 8 folded inwardly at right-angles to portions 5 to form the ends 9 of said lower part and have interlocking means, the tongues 10, en- 50 gaging in slits 11 for holding said flaps in proper relation.

55 The blank also comprises a pair of flaps 12 extending outwardly from the pair 5 (i. e., upwardly in the formed carton) and tapered as shown to form the sides 13 of the tapering upper part 14 of the carton, and the flaps 15 extending thus upwardly from one pair of flaps 8 and

tapered as shown to form the ends 16 of said tapered upper part. The flap portions 12 have end portions 17, which may be extended upwardly as seen in Figure 1 and have openings 18 which register with each other to receive the hand of a person carrying the carton; or these extending portions 17 may be folded to lap each other as shown in Figures 2 and 4 thus forming a closed top 19 for the carton. In said second-mentioned position these portions 17 are secured together 60 by interlocking means, as the inwardly extending tab 20 of one of said openings which is inserted into a suitable receiving slit 21 in the other portion 12.

In the illustrated construction the tapering 70 flap portions 15 have extensions 22 adapted to be folded horizontally inwardly and have means, as the interlocking tongues 23 for connecting them; and one of the tapering flap portions 12 has end flaps 24 adapted to be folded inwardly. The por- 75 tion 3 has end flaps 26 turned inwardly.

It will be seen that the lower parts of the bottles indicated at 25 in Figure 3 are held close together in the lower part 7 of the carton, their tapering upper ends being held in the carton's tapering 80 upper part 14; and that the carton may be closed at its top as shown in Figures 2 and 4 for storage, etc., or may be readily carried about in the position of the parts seen in Figure 1.

The invention being intended to be pointed out 85 in the claims, is not to be limited to or by details of construction of the particular embodiment thereof illustrated by the drawings or hereinbefore described.

I claim:

1. A carton rectangular in horizontal section comprising a lower part and a part tapering upwardly therefrom, made by bending a flat sheet comprising a rectangular middle portion forming the bottom of the carton and having end flaps turned inwardly, a pair of rectangular portions at the opposite sides of the middle portion forming the sides of said lower part of the carton each having a pair of end flaps forming the ends of said lower part and provided with interlocking means, tapering flaps extending from one pair of said end flaps forming the ends of said tapering upper part and provided with interlocking means, and comprising also a pair of portions tapering from said pair of rectangular portions forming the sides of said upper part and provided with interlocking means. 95

2. A carton rectangular in horizontal section comprising a lower part and a part tapering upwardly therefrom, made by bending a flat sheet 100

110

comprising a rectangular middle portion forming the bottom of the carton and having end flaps turned inwardly, a pair of rectangular portions at the opposite sides of the middle portion forming the sides of said lower part of the carton each having a pair of end flaps forming the ends of said lower part and provided with interlocking means, tapering flaps extending from one pair of said end flaps forming the ends of said tapering upper part and having extended portions bent toward each other and provided with interlocking means, and comprising also a pair of portions tapering from said pair of rectangular portions forming the sides of said upper part and provided with interlocking means.

3. A carton rectangular in horizontal section comprising a lower part and a part tapering upwardly therefrom, made by bending a flat sheet comprising a rectangular middle portion forming the bottom of the carton, a pair of rectangular portions at the opposite sides of the middle portion forming the sides of said lower part of the carton each having a pair of end flaps forming the ends of said lower part and provided with interlocking means, tapering flaps extending from one pair of said end flaps forming the ends of said tapering upper part and provided with interlocking means, and comprising also a pair of portions tapering from said pair of rectangular portions forming the sides of said upper part and provided with interlocking means.

4. A carton rectangular in horizontal section comprising a lower part and a part tapering upwardly therefrom, made by bending a flat sheet

comprising a rectangular middle portion forming the bottom of the carton, a pair of rectangular portions at the opposite sides of the middle portion forming the sides of said lower part of the carton each having a pair of end flaps forming the ends of said lower part and provided with interlocking means, flaps extending from one pair of said end flaps forming the ends of said tapering upper part, and comprising also a pair of portions tapering from said pair of rectangular portions forming the sides of said upper part and having hand-receiving openings therethrough.

5. A carton rectangular in horizontal section comprising a lower part and a part tapering upwardly therefrom, made by bending a flat sheet comprising a rectangular middle portion forming the bottom of the carton, a pair of rectangular portions at the opposite sides of the middle portion forming the sides of said lower part of the carton each having a pair of end flaps forming the ends of said lower part and provided with interlocking means, flaps extending from one pair of said end flaps forming the ends of said tapering upper part, and comprising also a pair of portions tapering from said pair of rectangular portions forming the sides of said upper part and having hand-receiving openings therethrough in mutual registration in one position of said last-mentioned pair of portions, said last-mentioned pair being adapted to be folded into lapping position forming the top of the carton and provided with securing means interlocking in said lapping position.
